UNITED STATES PATENT OFFICE

147,407

DESIGN FOR A TOASTER

George McStay Jackson, Chicago, Ill., assignor
to Camfield Manufacturing Company, Grand
Haven, Mich., a partnership

Application November 19, 1945, Serial No. 123,872

Term of patent 14 years

(Cl. D81—10)

To all whom it may concern:

Be it known that I, George McStay Jackson, a citizen of the United States, residing at Chicago, in the county of Cook and State of Illinois, have invented a new, original, and ornamental Design for Toaster, of which the following is a specification, reference being had to the accompanying drawings, forming part thereof.

Fig. 1 is a plan view of a toaster showing my new design.

Fig. 2 is a side elevational view thereof.

Fig. 3 is an end elevational view thereof.

I claim:

The ornamental design for a toaster, as shown.
GEORGE McSTAY JACKSON.
